UNITED STATES PATENT OFFICE.

RAY G. DETENBECK, OF BERTRAND, NEBRASKA.

HAT-BRIM HOLDER.

1,283,694.

Specification of Letters Patent.

Patented Nov. 5, 1918.

Application filed May 31, 1918. Serial No. 237,515.

To all whom it may concern:

Be it known that I, RAY G. DETENBECK, a citizen of the United States, residing at Bertrand, in the county of Phelps, State of Nebraska, have invented certain new and useful Improvements in Hat-Brim Holders; and I do hereby declare the following to be a full, clear, and exact description of the invention, such as will enable others skilled in the art to which it appertains to make and use the same.

The present invention relates to new and useful improvements in stiffening attachments for hats, more particularly of that type including a flat flexible brim.

In driving an automobile or under any other conditions involving a comparatively high wind pressure, considerable inconvenience is caused the wearers of hats of this nature by the flexure of the front portion of the brim, interfering with the sight of the wearer in flexing downwardly and tending to displace the hat in flexing upwardly.

It is the object of the present invention to provide a means for preventing this objectionable flexure of the hat brim and which does not itself form any inconvenience or obstruction to the sight of the wearer.

It is further an object to provide such a stiffening device for hat brims which may be most readily attached to and detached from a hat so that the hat may present an entirely normal appearance when the necessity for the use of the device is not present, and a more detailed object resides in the provision of such a device which is readily detachable to fit different widths of brims.

A still further object resides in the provision of such a device which is exceedingly simple in nature whereby it may be manufactured at a comparatively low cost.

With the above and other objects and advantages in view, the invention resides more particularly in the novel combination, formation and arrangement of parts hereinabove described and particularly pointed out in the appended claims.

In the accompanying drawings:

Figure 1 is a perspective view of the improved brim stiffening device applied to a straight brim hat of conventional nature.

Fig. 2 is a sectional view taken through the device longitudinally of one of the brim engaging arms thereof.

Fig. 3 is a perspective view of one of the brim engaging arms, looking toward its bottom.

Referring now more particularly to the accompanying drawings, the improved device comprises a body plate 5 curved to fit against the front portion of the crown of a hat adjacent its juncture with the brim, and this plate is detachably secured to the hat by a resiliently contractile band 6 passed about the crown of the hat and having its ends secured in apertures 7 in the ends of the plate.

Adjacent the ends of the plate, legs 9 are bent outwardly from its lower edge portion, and pivotally secured to these legs by rivets 10 are the inner ends of arms 11 which overlie the brim and rest on the upper surface thereof. Wings 12 are formed at the outer side portions of the arms and these wings are bent inwardly to underlie the bottoms of the arms and form channels for the reception of extension arm sections 13 each comprising a flat metal strip having its outer extremity bent in hook shape at 14 to embrace the outer edge of the brim. Thus by sliding the sections 13 inwardly or outwardly, the device is adjusted for brims of different widths, and the wings 12 preferably exert a resilient pressure against the extension sections 13 binding them within the channels formed by the wings and thus preventing accidental displacement of the side sections.

The method of application of the device to a hat is obvious, as is also the readiness with which the device may be attached or removed, and it is noted that the pivotal connections of the arms 11 with the body plate affords a further adjustment of the device for engaging the hat brim at the various portions most effective for holding the brim against undesired flexure.

What is claimed is:

1. A brim stiffening device for hats comprising a body plate, a contractile band having its ends secured to the body plate and adapted for disposition about the crown of the hat and an arm extending from the body plate and engageable with the brim to prevent flexure thereof.

2. A brim stiffening device for hats comprising a body member adapted for securing to a hat, an arm extending from said body member and engageable with the hat

brim to prevent flexure thereof and a hook formed on the outer end of the arm for embracing the edge portion of the brim.

- 5 3. A brim stiffening device for hats comprising a body member, means for securing said body member to a hat, an arm pivotally connected with the body member and a hook formed at the outer end of the arm for embracing the edge portion of the hat brim.
- 10 4. A brim stiffening device for hats comprising a body member, means for securing

said body member to a hat, an arm extending from the body member, a section extensibly carried by the arm and a hook formed at the outer end of the extension adapted to 15 embrace the edge portion of the hat brim.

In testimony whereof, I affix my signature, in the presence of two witnesses.

RAY G. DETENBECK.
